UNITED STATES PATENT OFFICE.

ALONZO C. GOODRICH, OF CHICAGO, ILLINOIS.

GOLF-CLUB.

1,206,105.

Specification of Letters Patent. Patented Nov. 28, 1916.

Application filed December 9, 1914. Serial No. 876,185.

To all whom it may concern:

Be it known that I, ALONZO C. GOODRICH, a citizen of the United States, and a resident of the city of Chicago, in the county of Cook and State of Illinois, have invented 5 certain new and useful Improvements in Golf-Clubs; and I do hereby declare that the following is a full, clear, and exact description of the same, reference being had to the accompanying drawings, and to the numerals of reference marked thereon, which form a part of this specification.

This invention relates to a golf club the striking head or blade of which is movable 15 upon the shaft, so that the head may be adjusted into various angles as required by the shot to be played.

It is an object of this invention to construct a golf club the head of which may be 20 turned through various angles, and yet held rigidly in all positions so that the single club is well adapted for practically any kind of shot, and consequently it is unnecessary for a player to carry and use more than 25 the one club.

It is also an object of this invention to construct a golf club the head of which may be turned through various angles to present a striking face of certain inclination to the 30 ball, dependent upon the shot to be played.

It is also an important object of this invention to construct a golf club the head of which may be turned upon the shank into any desired position, the adjusting means 35 acting to hold the head from movement from its adjusted position.

It is furthermore an important object of this invention to construct a golf club the head of which is pivoted upon the shank 40 and guided in its movement by suitable interfitting tongue and groove members and provided with a small worm and gear, the worm when actuated serving to move the head and maintaining the same in any desired 45 position of adjustment.

It is finally an object of this invention to construct a golf club consisting of few parts, the head of which is adjustable upon the shank to vary the angle of the striking face 50 of the head, so that the club is well adapted for different shots to be played.

The invention (in a preferred form) is illustrated in the drawings and hereinafter more fully described.

55 In the drawings: Figure 1 is a front ele-

vation of the shank and head of a golf club embodying the principles of my invention with the shaft omitted. Fig. 2 is a rear end view thereof. Fig. 3 is a top plan view thereof. Fig. 4 is a detail section taken 60 on line 4—4 of Fig. 3. Fig. 5 is a face view of the lower end of the shank, with the head detached therefrom. Fig. 6 is a detail section taken on line 6—6 of Fig. 1. Fig. 7 is a front elevation of a modified form of 65 device. Fig. 8 is a rear end view thereof. Fig. 9 is a front end view thereof showing the operation in dotted lines. Fig. 10 is a top plan view thereof. Fig. 11 is a fragmentary view of one end of the head of the 70 type of club shown in Fig. 1, detached from the shank. Fig. 12 is a similar fragmentary view of the end of the head of the type of club shown in Fig. 7.

As shown in the drawings: The device as 75 illustrated in Figs. 1 to 6 inclusive and Fig. 11, comprises a hollow tapered shank 1, adapted to receive the end of a shaft therein, and provided at its end with an integral heel piece 2, at an angle thereto, which is 80 cored out to receive a small worm 3, journaled therein and secured on or integral with a shaft 4, one end of which projects through an aperture in the side of said heel piece, and is provided thereon with a 85 knurled head 5. The striking head or blade of the club is indicated as a whole by the reference numeral 6, and at its end adjacent said heel piece 2, is provided with an integral stud having teeth cut therein affording 90 an elongated worm wheel 7. A small screw 8, is engaged through an aperture in the rear face of the heel piece 2, and threaded into said worm wheel stud 7, to maintain the head of the club associated with said shank 95 and heel piece. A downwardly projecting curved tongue 9, is formed integral with the upper portion of said heel piece 2, and interfits with a complementally curved groove 10, formed on the inner end of the striking 100 head 6, of the club.

In the modification of my device illustrated in Figs. 7 to 10 inclusive and Fig. 12, the shank is indicated by the reference numeral 11, and the heel piece integral therewith and cored out as before, by the reference numeral 12, but in the present instance said heel piece is in line with the shank. As clearly shown in Fig. 12, the striking head 105 or blade of the club, indicated by the refer- 110

ence numeral 13, is provided with a gudgeon or elongated worm wheel 14, the axis of which is at an angle to the axis of the head. As before a small screw 15, engages through the rear surface of the heel piece 12, and threads into the gudgeon or worm wheel 14, to hold the head associated with the shank and heel piece of the club. Said head is also provided with a curved groove 16, into which a tongue 17, integral with the upper portion of the heel piece interfits, assisting in maintaining the head of the club in proper relation to the shank and heel piece thereof.

15 Another feature of the present construction differentiated from that illustrated in Fig. 1, is that the abutting face of the heel piece and striking head is not at right angles to a plane through the axis of the shank and the axis of the head, as clearly shown in Fig. 10. The purpose of angling the abutting face in such a manner, and of course the tongue 17, therewith, is to cause a component of the stress transmitted through the club when a ball is struck thereby, to be resisted by the angled face of said heel piece and not entirely by the pivotal support or gudgeon 14, of the striking head. As in the construction previously described, 20 a worm is journaled within said heel piece meshing with the elongated worm wheel 14, to adjust said head through various positions and maintain the same so adjusted, and a knurled head 18, is provided on the 25 outer end of the worm shaft to effect ready adjustment of the worm.

In both of the constructions described, as clearly shown in Figs. 3 and 10, a number of graduations are provided on the upper 30 surface of the heel piece along the edge of the tongue member thereof, and an indicating mark is provided on the abutting edge of the striking head to readily designate a predetermined or any desired adjustment of the head with respect to the shank and shaft of the club.

Another important feature of construction in the modification shown, is what may be termed the eccentric mounting of the striking head or blade in the heel piece, that is the axis of the pivot of the striking head is not in line with the axis of the shank, but instead is offset rearwardly a slight amount as clearly shown in Figs. 8, 9, and 50 10. Thus the club when used as a putter, that is with the blade in a substantially vertical position, approximates in form the well known type of "goose-neck" club which has come into such great favor. Of course, 55 however, when the angle of the blade is changed to any other position, the lower edge thereof is advanced forwardly, so that the proper desired alinement of the blade and the axis of the shank or shaft is secured.

60 65 The construction of the device is such

that there are no projections on the front portion of the shank or striking head, and the lower edge of the club is in line with, or very closely in line with, the lower front edge of the heel piece 2, in all adjustments 70 of the striking head, an almost essential feature in the construction of a golf club. The worm and worm wheel form an admirable means for adjusting the striking head into various positions, for the reason that 75 such a mechanism being irreversible, the head is positively held in such position, and cannot be moved therefrom except by turning the knurled head which actuates the worm.

I am aware that various details of construction may be varied through a wide range without departing from the principles of this invention, and I therefore do not purpose limiting the patent granted 85 otherwise than necessitated by the prior art.

80 I claim as my invention:

1. In a golf club of the class described, a shank, a heel piece integral therewith, a head pivoted in said heel piece, a worm 90 wheel connected to said head, and a worm journaled in said heel piece adapted to adjust the head into various positions.

2. In a device of the class described, a shank, a heel piece integral therewith, a 95 head pivoted in said heel piece, and worm and worm gear connections between said heel piece and said head whereby the head may be adjusted in said heel piece and held from movement therein.

100 3. In a golf club of the class described, a shank, a head pivotally mounted thereon, interfitting tongue and groove members on said shank and head respectively to guide and retain the same in proper relation during movement thereof, and worm and worm wheel connections between said shank and head whereby an adjustment is effected between the two.

4. In a device of the class described, a 110 shank, a heel piece integral therewith, rotatable means therein, a head, toothed means thereon adapted to engage said rotatable means to permit changing the angle of the striking face of the device, the connection 115 between said head and heel piece being such as to also change the alinement between the axis of the shank and the axis of the head when said head is adjusted.

5. In a device of the class described, a 120 shank, a heel piece integral therewith, a head pivoted thereon, and rotatable means within said heel piece to permit adjustment of said head through various striking angles.

125 6. In a golf club of the class described, an adjustable head eccentrically pivoted, and worm and worm wheel connections for adjusting the same into various positions.

7. In a golf club of the class described, 130

a shank, an adjustable head thereon, and worm and worm wheel connections for adjusting the head into various positions.

8. In a golf club of the class described, 5 a shank, a head pivoted thereon, and rotatable means within said shank for adjusting the head into various positions.

9. In a golf club of the class described, a shank, a heel piece integral therewith, 10 adjusting means within said heel piece, a head pivoted in said heel piece, and means integral therewith adapted to engage said adjusting means to position the head through various striking angles.

10. In a golf club of the class described, 15 a shank, a heel integral therewith, a worm movably mounted therein, a head, and a worm wheel integral therewith adapted to engage said worm to adjust said head through different angles.

In testimony whereof I have hereunto subscribed my name in the presence of two subscribing witnesses.

ALONZO C. GOODRICH.
